UNITED STATES PATENT OFFICE.

DORFIS A. BROWN, OF PIERCE, WEST VIRGINIA.

SWITCH-HINGE AND HEEL-PLATE.

1,371,851.

Specification of Letters Patent. Patented Mar. 15, 1921.

Application filed July 3, 1919. Serial No. 308,407.

To all whom it may concern:

Be it known that I, DORFIS A. BROWN, a citizen of the United States of America, residing at Pierce, in the county of Tucker 5 and State of West Virginia, have invented new and useful Improvements in Switch-Hinges and Heel-Plates, of which the following is a specification.

The object of the invention is to provide 10 a new and novel means for connecting the switch point to a section of the main track in railroad construction. To this end the invention comprises a chair in which the end of the main track section seats, this 15 chair being formed with a heel plate for the pivoted end of the switch point. An angle bar clamps against the main track section and to the chair and it and the heel plate support a pin on which the switch is 20 pivoted by means of an eye formed at its base flange.

Illustrated and described in a specific embodiment, the invention is not to be restricted to such. The right is reserved to 25 make such changes or alterations as the actual reduction to practice may suggest, in so far as such changes or alterations are compatible in spirit with the annexed claims.

30 The same numerals of reference designate the same parts throughout the several figures of the drawings, wherein:

Figure 1 is a view in side elevation of the invention.

35 Fig. 2 is a top plan view.

Fig. 3 is a section on the line 3—3 of Fig. 1.

Fig. 4 is a section on the line 4—4 of Fig. 1.

40 Fig. 5 is a top plan view of the chair comprising a part of the invention.

Referring to the drawings, there is shown 45 that end of the rail section 1 to which the switch point 2 is connected. This end of the rail section consists in an appropriate chair comprising the base plate 3 and the base and web engaging section 4. The switch point 2 also rests in this chair at its pivot end, the base plate of the chair being 50 the heel plate of the switch point. An angle bar 5 is secured to the rail section 1 on the opposite side from the section 4 of the chair, bolts 6 being employed for the purpose of such attachment. The angle bar is 55 shorter than the section 4 of the chair but is of sufficient length to extend beyond the

section 1 and overlap the pivot end of the switch point 2. The inner face of the web engaging portion of the angle bar 5 at that end which overlaps the switch point is 60 beveled or tapered off as indicated at 7.

The flange engaging portion of the angle bar 5 and the base plate 3 are each formed with a hole 8, while the base flange of the switch point 2 is simply formed with a hole 65 9 which registers with the holes 8, a pin 10 being passed through the three to provide a pivot point for the switch point 2. The pin 10 is enlarged in diameter where it passes through the base flange of the switch 70 point. Shoulders are thus formed on opposite sides of the enlarged portion and bear respectively against the base flange 3 and the angle bar 5. Vertical movement of the pin is thus prevented and it is maintained 75 in place to provide the pivot for the switch point.

Base plate 3 of the chair is, as indicated in Figs. 2 and 5 of the drawings, tapered in the direction of its length on one side, 80 that part of the base plate receiving the switch point being the widest, so that there may always be a heel portion for the base of the switch point to rest upon when the switch point is swung to either of its two 85 positions which it is necessary for it to assume in practice.

The chair is cut away as indicated at 11 to provide a space for spikes in attaching the device to a tie and the chair is formed 90 at the base plate with an opening 12 extending as shown at 13, and an opening at the side of the base plate, so that an implement may be inserted between the end of the rail section 1 and the switch point to 95 clear the two from dirt which may be between them. This dirt may be forced down through the opening 12.

Obviously in operating the switch point it swings on the pin as a pivot the portion 100 14 of the chair serving to limit the switch point to a position in alignment with the rail section 1 and the beveled portion 7 of the angle bar 5 permitting the switch point to swing inwardly to a position at an angle 105 with reference to the section 1.

The invention having been described, what is claimed as new and useful is:

1. In a device of the kind described, the combination with a rail section, of a switch 110 point having one end disposed adjacent the end of the rail section, a chair in which the

ends of the rail section and switch point seat and comprising a base plate and a base and web engaging section, an angle bar disposed against the rail section and overlapping the end of the switch point, means securing the angle bar, the rail section and the web engaging section of the chair together, and a pin passing through one flange of the angle bar and through the 10 flange of the switch point and through the base plate, whereby the switch point is pivotally connected to the chair and to the angle bar for the purpose specified.

2. In a device of the kind described, the 15 combination with a rail section, of a switch point having one end disposed adjacent the end of the rail section, a chair in which the ends of the rail section and switch point seat and comprising a base plate and a base and web engaging section, an angle bar disposed against the rail section and overlapping the end of the switch point, means securing the angle bar, the rail section and the web engaging section of the chair together, and a pin passing through one flange 20 of the angle bar and through the base plate and having an enlarged intermediate portion bearing respectively against the base

plate and the angle bar and being seated in an opening formed in the base of the switch 30 point to provide a pivotal connection for the latter.

3. In a device of the kind described, the combination with a rail section and switch point having their two ends adjacent each 35 other, of a chair comprising a base plate and a web flange engaging portion, the rail section and the switch point being seated in the chair and disposed against the web engaging portion thereof, an angle bar disposed against the rail section and overlapping the adjacent end of the switch point, means securing the web engaging section, the rail section and the angle bar together, and a pivotal connection between the switch 40 point and angle bar and base plate, the base plate being formed with an opening therein disposed below the adjoining ends of the rail section and the switch point and extending laterally of the base plate and opening through the side of the latter below the base and web engaging portion of the chair, whereby foreign matter between the rail section and the switch point may be ejected.

In testimony whereof I affix my signature. 55
DORFIS A. BROWN.
